CYLINDRICAL CONTAINER CONSTRUCTION
Harry W. Lee, Jr., Chesterfield County, Va., assignor to
Reynolds Metals Company, Richmond, Va., a corpora-
tion of Delaware
Filed Mar. 26, 1965, Ser. No. 442,965
8 Claims. (Cl. 229—4.5)

ABSTRACT OF THE DISCLOSURE

This disclosure relates to a method of making cylindrical container bodies by providing an elongated rectangular flat board means and applying lining means to one side thereof and label means to the other side thereof so that the board means can be subsequently convolutely wound to provide a plurality of cylindrical container bodies each having the lining means forming the entire interior surface thereof and the label means forming the entire exterior surface thereof, the flat board means having sealing means disposed thereon in transverse, parallel and spaced relation so that each resulting container body will have an annular band of sealing means at the opposed ends thereof to cooperate with end closures subsequently closing the ends to provide a sealing means for such end closures.

This invention relates to an improved convolutely wound container or the like as well as to improved board means for making such a container or the like. In addition, this invention relates to an improved method of making such a container or such a board means.

It is well known that various containers can be formed by convolutely winding board means on a mandrel so that the individual container bodies can be subsequently cut from the container body stock issuing from the end of the mandrel to have the open ends thereof subsequently closed by suitable end closures after the container bodies have been filled with a desired product.

However, it has been found that no fully automatic and economical means have been provided for effecting a fluid sealing between the end closures and the container bodies.

According to the teachings of this invention, however, improved means are provided for automatically and economically providing a sealing means at the ends of the container bodies to be engaged by the end closures closing the open ends of the container bodies to provide a fluid seal therewith.

Accordingly, it is an object of this invention to provide an improved container having one or more of the novel features of this invention as set forth above or herein-after shown or described.

Another object of this invention is to provide an improved board means for making such a container or the like.

A further object of this invention is to provide an improved method for making such a container means or the like.

Another object of this invention is to provide an improved method for making such a board means or the like.

Other objects, uses and advantages of this invention are apparent from a reading of this description which proceeds with reference to the accompanying drawings forming a part thereof and wherein:

FIGURE 1 is a plan view of an improved board means of this invention.

FIGURE 2 is a perspective view of one blank of the board means of FIGURE 1.

2

FIGURE 3 is a cross-sectional view taken on line 3—3 of FIGURE 2.

FIGURE 4 is an end view of the blank of FIGURE 2.

5 FIGURE 5 is a top perspective view illustrating the blank of FIGURE 3 convolutely wound into a container body.

FIGURE 6 is a large, fragmentary, cross-sectional view taken on line 6—6 of FIGURE 5.

10 FIGURE 7 is an enlarged, fragmentary, cross-sectional view of the container body of FIGURE 5 having an end closure secured thereto according to the teachings of this invention.

FIGURE 8 is a cross-sectional view of another embodiment of the end closure of this invention.

15 FIGURE 9 is a view similar to FIGURE 1 and illustrates another embodiment of this invention.

FIGURE 10 is a view similar to FIGURE 2 and illustrates a blank from the board means of FIGURE 9.

20 FIGURE 11 is a cross-sectional view taken on line 11—11 of FIGURE 10.

While the various features of this invention are herein-after described and illustrated as being particularly adaptable to provide a convolutely wound container, it is to be understood that the various features of this invention 25 can be utilized singly or in any combination thereof to provide other devices as desired.

Therefore, this invention is not to be limited to only the embodiments illustrated in the drawings, because the drawings are merely utilized to illustrate one of the wide 30 variety of uses of this invention.

Referring now to FIGURE 1, an improved blank means for forming convolutely wound container bodies is generally indicated by the reference numeral 20 and is fully illustrated in FIGURES 1—4.

35 The blank means 20 comprises a sheet of flat cardboard-like means 21 for forming the container body structure of the containers of this invention. A strip of lining material, 22, such as metallic foil or a lamination containing metallic foil is secured to the side 23 of the board 21 in any suitable manner and has one end 24 thereof overlapping the end 25 of the board 21 while the other end 26 thereof extends substantially slightly greater than one-half of the length of the board 21, the foil side of the lining material 22 facing outwardly to provide a moisture barrier against the product in a manner hereinafter described.

40 A wrapper or label strip 27, such as aluminum foil or a lamination containing aluminum foil, is secured to the side 28 of the board 21 and has an end 29 overlapping the end 30 of the board 21 while the other end 31 of the wrapping material 27 extends slightly over one-half of the length of the board means 21, the foil side of the lining material 22 facing outwardly to provide a moisture barrier on the exterior surface of the resulting containers in a manner hereinafter described.

45 However, it is to be understood that the lining material 22, wrapping material 27 and board 21 can be formed of other materials, as desired.

50 After the blank 20 has been formed in the manner previously described, sealing means, such as a hot melt wax-like material or the like is applied in spaced parallel strips 32 on the label means 27 and in spaced parallel strips 33 on the liner means 22 in the pattern illustrated in FIGURES 1—3.

55 After the sealing means 32 and 33 has hardened, the blank 20 illustrated in FIGURE 1 can be convolutely wound in a continuous manner on a stationary mandrel in a manner well known in the art whereby the board means 20 is convolutely wound upon itself so that the 60 lining means 22 will form the interior of the container body stock and the wrapper means 27 will form the exterior thereof, the convolutely wound board means

65

20 being secured together by any suitable adhesive or the like in a conventional manner.

Thereafter, the convolutely wound container body stock issuing from the end of the stationary mandrel is automatically cut into a plurality of container bodies 34, FIGURE 5, in a manner well known in the art, along the lines 35 illustrated in FIGURE 1 whereby the sealing means 32 and 33 will be at each end of the container bodies 34.

Alternately, the blank means 20 illustrated in FIGURE 1 can be separated along lines 35 to provide the 10 small blanks 20 illustrated in FIGURE 2 to individually form the convolutely wound container bodies 34.

In any event, the resulting container bodies 34 illustrated in FIGURE 5 will each have the band means 32 and 33 of the sealing compound disposed at the opposed 15 open ends 36 and 37 of the container body 34 in the manner illustrated in FIGURES 5 and 6.

In order to close the open ends 36 and 37 of the container body 34, after the same has been filled with the desired product, a suitable end closure 38, FIGURE 7, is 20 crimped over one of the ends 36 and 37 in the manner illustrated in FIGURE 7 whereby the curled bead 39 of the end closure 38 fully engages the sealing means 32 and 33 to provide a fluid seal therewith.

If desired, the sealing means 32 and 33 can be heat activated so that during the curling operation of the bead 39 of the end closure 38 with the respective end 36 or 37 of the container body 34, the forming roller can be heated to activate the sealing means 32 and 33 to further enhance the sealing effect between the bead 39 and the end 36 or 37 of the container body 34.

If desired, the end closure 38 can also contain sealing means 40 in the manner illustrated in FIGURE 8 to complement the sealing means 32 and 33 carried by the container body 34 in the manner previously described.

Therefore, it can be seen that the blank 20 formed according to the teaching of this invention can be automatically convolutely wound on a stationary mandrel or the like with the band means 32 and 33 of the sealing means so disposed thereon that as the resulting container body stock issues from the stationary mandrel, the same can be cut into individual container bodies 34 along the lines 35 illustrated in FIGURE 1 to produce the container bodies 34 having the sealing means 32 and 33 at the opposed ends 36 and 37 thereof to provide the fluid-tight seal with the end enclosures 38 subsequently utilized to close the open ends 36 and 37 in the manner previously described.

If desired, the sealing means at the ends 36 and 37 of the container body 34 can be disposed only on the liner means 22 thereof if desired by merely not placing the bands 32 on the blank 20 illustrated in FIGURE 1.

Also, the same sealing means which forms the bands 33 on the insides of the container body 34 can be part of an adhesive pattern placed on the blank 20 to secure together the overlapping portions of the convolutely wound board 20.

In particular, reference is made to FIGURES 9-11 wherein another blank means of this invention is generally indicated by the reference numeral 41 and comprises the board means 21A previously described having the strip of lining means 22A secured thereto and the strip 27A of wrapping material secured thereto in the manner previously described.

However, sealing means 42 is disposed on the board means 21A to provide the means for securing together the overlapping portions of the convolutely wound blank 41, the sealing means 42 also defining the bands 33A which will subsequently provide the annular bands on the inside of the resulting container body in the same manner as the bands 33 illustrated in FIGURE 5.

Therefore, it can be seen that the same sealing means utilized to secure together the overlapping portions of the convolutely wound blank 41 will also provide the sealing

means for the end closures 38 subsequently utilized to close the open ends of the resulting container bodies.

Therefore, it can be seen that this invention has not only provided an improved blank or board means for forming a convolutely wound container, but also this invention has provided an improved convolutely wound container.

In addition, this invention has provided an improved method of making such board means and/or container.

While the form of the invention now preferred has been disclosed as required by the statutes, other forms may be used, all coming within the scope of the claims which follow.

What is claimed is:

1. In combination, a single flat rectangular board means having opposed side means and being adapted to be convolutely and longitudinally wound to define a plurality of container bodies each having opposed opened ends, and sealing means disposed on said side means of said board means and transverse, parallel and spaced relation to subsequently define annular band means at each end of each container body to be engaged by respective end closures subsequently closing said ends.

2. A combination as set forth in claim 1 wherein said band means will only be on the inside of said container bodies.

3. A combination as set forth in claim 1 wherein said band means will be on both sides of said container bodies.

4. A combination as set forth in claim 1 wherein each band means extends throughout substantially one-half of the length of said board means so that said board means can be convolutely wound upon itself.

5. In combination, a single flat rectangular board means having opposed side means and being adapted to be convolutely and longitudinally wound to define a plurality of container bodies each having opposed opened ends, liner means disposed on one side means of said board means to define interior surface means of said container bodies, wrapper means disposed on the other side means of said board means to define exterior surface means of said container bodies, and sealing means disposed on said liner means and transverse, parallel and spaced relation to subsequently define annular band means at each end of each container body to be engaged subsequently by respective end closures closing said ends.

6. A combination as set forth in claim 5 wherein sealing means is also disposed on said wrapper means in transverse, parallel and spaced relation to subsequently define annular band means at each end of each container body to be engaged by said end closures.

7. A combination as set forth in claim 5 wherein said liner means and said wrapper means overlap the ends of said board means.

8. A combination as set forth in claim 5 wherein said liner means extends throughout substantially one-half of said board means and said wrapper means extends throughout substantially one-half of said board means whereby said board means can be convolutely wound upon itself.
